UNITED STATES PATENT OFFICE

EDWARD A. DOMES, OF SAN GABRIEL, CALIFORNIA, ASSIGNOR OF ONE-HALF TO OLIVER
P. WALKER, OF SAN GABRIEL, CALIFORNIA

DESIGN FOR A BARBECUE BROILER

Application filed May 2, 1932. Serial No. 43,692. Term of patent 3½ years.

To all whom it may concern:

Be it known that I, EDWARD A. DOMES, a citizen of the United States, and a resident of the city of San Gabriel, county of Los Angeles, and State of California, have invented a new, original, and ornamental Design for a Barbecue Broiler, of which the following is a specification, reference being had to the accompanying drawing forming part thereof, in which:

The single figure is a perspective view of the barbecue broiler embodying my invention.

The dominant feature of the design is the configuration of the barbecue frame.

I claim:

The ornamental design for a barbecue broiler substantially as shown and described.

EDWARD A. DOMES.
